Primary Examiner — Mark Goodwin**CLAIM**

The ornamental design for a front end final loader, as shown and described.

DESCRIPTION

FIG. 1 is a perspective view of a front end final loader of the present invention.

FIG. 2 is a left side view of the front end final loader of FIG. 1.

FIG. 3 is a right side view of the front end final loader of FIG. 1.

FIG. 4 is a top view of the front end final loader of FIG. 1.

FIG. 5 is a bottom view of the front end final loader of FIG. 1.

FIG. 6 is a rear view of the front end final loader of FIG. 1; and,

FIG. 7 is a front view of the front end final loader of FIG. 1.
